DENTAL BRIDGE

Irving Quellman, New York, N. Y.

Application June 29, 1951, Serial No. 234,361

9 Claims. (Cl. 32—6)

1

This invention relates to dental bridges, more particularly of the fixed type.

As conducive to an understanding of the invention it is noted that the abutment teeth on each side of the gap in the mouth in which a bridge is to be placed are often not parallel and cannot be made so due to limitations in the precision with which such teeth are ground by the dentist and due to the degree of inclination of the abutment teeth which would require such an amount of grinding to effect parallelism that the nerves of the teeth might be affected. It is therefore extremely difficult if not impossible properly to install a fixed bridge having crowns at each end which fit over such abutment teeth as the inclination of one of said abutment teeth with respect to the other would prevent proper seating of the crowns of the fixed bridge on the associated abutment teeth with resultant space between the rim of the mouth of the crown and the gum into which food might collect with resultant decay of said abutment teeth.

It is also to be noted that even though the anchoring or abutment teeth on each side of the gap in the mouth in which the bridge is to be placed, are carefully prepared for the anchoring portions of the bridge, which may be inlays or crowns that are to be cemented on the abutment teeth to hold the bridge in place, and even though an accurate cast and model is made, due to the expansion and contraction of the materials used, the inlays or crowns, as the case may be, on each end of the bridge respectively may become relatively displaced so that they both will not accurately seat on the abutment teeth. As a result, when inlays are used, there may be a slight gap between the edges of at least one of the inlays and the tooth, or when crowns are used at least one of such crowns may not reach the gum line and snugly encompass the abutment tooth with the result that food particles may collect beneath the inlay or crown with resultant decay of the abutment tooth.

Where the bridge is capable of lateral displacement in the mouth, it will be very uncomfortable to the user and prevent proper chewing. In addition, such displacement may become aggravated with repeated use causing excessive pressure on the abutment teeth with consequent displacement and possible loss of such teeth.

Where bridges are used which have clamps or other elements protruding therefrom, such elements are likely to injure the gum or tongue of the user and in addition food particles may collect therebeneath with resultant development of disagreeable odors and decay.

It is accordingly among the objects of the invention to provide, in situations where a removable bridge is indicated or a permanent bridge could be applied only by complicated and costly

2

procedure with objectionable building up of the abutment teeth or anchoring portion of the bridge due to lack of parallelism of the abutment teeth, a substantially permanent dental bridge that may readily be fabricated by a dentist or dental technician and has but few parts, which is strong, durable and non-corrosive and not likely to become deranged, and when once installed does not have to be removed for cleaning or sterilization, which bridge may readily be installed in the mouth, using substantially conventional crowns or inlays on the abutment teeth even when the latter are not parallel, without need for many fittings and grinding which give discomfort to the patient, yet will accurately fit in place with no space between the abutment teeth and the anchoring portions of the bridge mounted thereon, thereby eliminating the possibility of decay of such abutment teeth due to the collection of food particles between the anchoring portion of the bridge and the abutment tooth, which bridge is devoid of protruding clasps or other elements that may injure the mouth of the user and which, when once installed, will be securely and permanently retained in place without likelihood of lateral displacement which might affect the bite of the user and cause excessive pressures to be exerted against the abutment teeth with resultant injury to and possible loss of such teeth.

According to the invention from its broader aspect, the dental bridge comprises at least one artificial tooth having an anchoring member, which may be a crown or inlay, associated therewith and rigidly affixed thereto on one side thereof. The artificial tooth desirably has a locking member mounted therein so as to extend outwardly from the other side wall of the tooth in a plane substantially parallel to the biting surface of the tooth and said locking member seats in a socket formed in a second anchoring member such as a crown or an inlay, the dimensions of the socket and the locking member being so related that although the locking member is free to move longitudinally and rotate in said socket, it will substantially be restrained from lateral displacement therein.

More specifically according to one embodiment of the invention, the locking member desirably comprises a spring urged plunger slidably mounted in said artificial tooth and having its longitudinal movement outwardly of the tooth limited by means of an internal projection in the tooth which coacts with the plunger so that the outer end thereof will project only sufficiently to seat in said socket.

In the accompanying drawings in which are shown one or more of various possible embodiments of the several features of the invention,

Fig. 1 is a fragmentary plan view of the upper portion of a mouth showing a plurality of arti-

ficial teeth mounted according to one embodiment of the invention.

Fig. 2 is a longitudinal sectional view taken along line 2-2 of Fig. 1.

Fig. 3 is a detail longitudinal sectional view on a larger scale taken along line 3-3 of Fig. 2.

Fig. 4 is an exploded perspective view on a larger scale showing the locking assembly.

Fig. 5 is a fragmentary plan view of the upper portion of the mouth showing another embodiment of the invention incorporated in a bridge having a single artificial tooth.

Fig. 6 is a longitudinal sectional view taken along line 6-6 of Fig. 5, and

Fig. 7 is a longitudinal sectional view of still another embodiment of the invention.

Referring now to the drawings, the embodiment of the dental bridge shown in Figs. 1 to 4 desirably comprises a plurality of artificial teeth, illustratively three in number designated 11, 12 and 13 which may be made of any suitable material such as plastic. The tooth 11 has an anchoring member 15, illustratively a crown of conventional type, rigidly affixed thereto by means of a lateral extension 16 on said crown which is molded into the tooth 11 when the latter is formed. As the formation of such teeth and crown is well known to those skilled in the art, it will not be described.

The tooth 13 has a lateral bore 17 therein through the side wall 18 thereof adjacent the biting surface 19 and substantially parallel to the latter. Affixed in said bore 17 in any suitable manner, such as by molding when the plastic tooth is formed, is a sleeve 21 desirably of non-corrosive material such as an alloy of gold and platinum. The sleeve 21 has a wall 22 at one end and its open end 23 is substantially flush with the side wall 18 of tooth 13.

Slidably mounted in sleeve 21 is a locking member, preferably a plunger or latch 24 also desirably of an alloy of gold and platinum. The plunger desirably has a diameter but slightly less than the inner diameter of the sleeve so that it may freely slide therein, but will be restrained from lateral displacement. The plunger is normally urged out of the open end 23 of the sleeve by means of a coil spring 25, preferably of stainless spring steel, compressed between end wall 22 and the adjacent end 26 of plunger 24. Suitable means are desirably provided to limit the outward movement of the plunger under the urging of coil spring 25. Such means may comprise a pin 27 extending substantially radially into sleeve 21 through an opening 28 in the wall thereof and into an annular groove 29 formed in the plunger, the pin being entirely contained within the sleeve so that it does not protrude therefrom and desirably being tapered so that when driven into opening 28 it will securely be retained in position.

Associated with plunger 24 is a cup 31 also preferably of a non-corrosive alloy of gold and platinum. The cup 31 has an internal diameter but slightly greater than the diameter of the plunger so that the front end 32 of the latter may freely slide into the cup and rotate therein, but is restrained from lateral displacement therein. The cup 31 is desirably rigidly mounted as by casting in a socket 33 in an anchoring member, illustratively a crown 34 of conventional type and desirably extends laterally in said crown so that its mouth 35 is flush with the side wall 36 thereof.

The groove 29 in plunger 24 is of such width that when the side wall 31 thereof abuts against pin 27 as shown in Fig. 3, the front end 32 of the

plunger will project beyond the open end of the sleeve 21 into cup 31 with a portion of such front end 32 in advance of the groove 29 still encompassed by said sleeve. As a result, even in projected position the plunger will still be restrained from lateral displacement.

In the fabrication of the bridge shown in Figs. 1 to 4 inclusive, the abutment teeth 41 and 42 are prepared to receive a crown and an impression is taken of the prepared teeth 41, 42 as well as the space therebetween in which the artificial teeth 11, 12 and 13 are to be positioned. As the preparation of the teeth 41 and 42 for this purpose, as well as the taking of the impression, is well known to those skilled in the art, it will not be described.

The plunger 24 and coil spring 25 are positioned in the sleeve 21 and the tapered pin 27 is forced into the opening 28 so that its inner end will be positioned in the annular groove 29 in the plunger. The portion of the pin protruding from the exterior of the sleeve is thereupon broken away. The sleeve and its contained plunger and spring are molded into tooth 11 and the cup 31 is cast into the side wall 36 of crown 34 as above described.

In installing the bridge shown in Figs. 1 to 4, the crown 34 which is previously filled with suitable cement is positioned over abutment tooth 42 and pressed in place in conventional manner so that it will seat in the position shown in Fig. 2 with the rim 43 of the mouth of the crown against the gum line. After the cement in crown 34 has hardened and the crown is firmly affixed to the abutment tooth 42, the teeth 11, 12 and 13 and crown 15 are positioned in the space between abutment teeth 41, 42 with the crown 15 which is filled with cement aligned with tooth 41. The artificial teeth and crown 15 are then pressed into the gap between teeth 41 and 42 so that the crown 15 may encompass abutment tooth 41. As the artificial teeth move into the gap, the end 32 of the plunger will abut against the edge 44 of crown 34 and be cammed into sleeve 21. When the crown 15 has properly seated on tooth 41 so that its rim 45 is against the gum line, the plunger 24 will snap into the socket 31 to lock the artificial teeth in position.

With the above construction it is apparent that even if the abutment teeth 41, 42 are not parallel, as shown in Fig. 2, both crowns will properly seat on the associated abutment teeth and the bridge will be securely and permanently affixed in place with no space between the rims of the crowns and the gum line into which food might collect with resultant decay of the abutment teeth.

In the embodiment shown in Figs. 5 and 6 the dental bridge desirably comprises an artificial tooth 51 which may be made of any suitable material and also desirably is of plastic. The tooth 51 has an anchoring member 52, illustratively an inlay of conventional type, rigidly affixed thereto by means of a lateral extension 53 on said inlay which is molded into the tooth 51 when the latter is formed.

The tooth 51 has a lateral bore 54 therein through the side wall 55 thereof adjacent the biting surface 56 and substantially parallel to the latter. Affixed in said bore 54 in any suitable manner, such as by molding when the plastic tooth is formed, and extending laterally outwardly from the side wall 55 of tooth 51 is a locking member which may comprise a pin 57 desirably of non-corrosive material such as an alloy of gold and platinum.

Associated with pin 57 is a cup 59 also preferably of a non-corrosive alloy of gold and platinum. The cup 59 has an internal diameter but slightly greater than the diameter of the pin 57 so that the latter may freely slide into the cup, but is restrained from lateral displacement there-in. The cup 59 is desirably rigidly mounted as by casting in a socket 61 in an anchoring member, illustratively an inlay 62 of conventional type and desirably extends laterally in said inlay so that its mouth 63 is flush with the side wall 64 thereof.

In the fabrication of the bridge shown in Figs. 5 and 6, the abutment teeth 66 and 67 are prepared to receive an inlay and an impression is taken of the prepared teeth 66, 67 as well as the space therebetween in which the artificial tooth 51 is to be positioned. As the preparation of the teeth for this purpose as well as the taking of the impression is well known to those skilled in the art, it will not be described.

In installing the bridge including inlays 52 and 62 and the tooth 51, the outer end of the pin 57 is inserted into the cup 59 which is longitudinally aligned therewith, in which position the 25 biting surfaces of the inlays and tooth will lie in substantially the same plane as shown in Figs. 5 and 6. The assembled bridge is then positioned in the mouth of the patient so that the inlays are over the abutment teeth 66 and 67 which have 30 been previously covered with a suitable cement and the bridge is pressed in place.

By reason of the longitudinal and rotary displacement afforded by the locking assembly between inlay 62 and tooth 51, the two inlays automatically adjust themselves as they are pressed into place so that they both will accurately seat in the previously prepared abutment teeth 66 and 67 with no space between the edges of the inlays and the biting surfaces of the teeth.

In the embodiment shown in Fig. 7, parts corresponding to those shown in Figs. 5 and 6 have the same reference numerals primed. In this embodiment the locking assembly is shown incorporated in a bridge having a plurality of teeth positioned, for example, in the front of the mouth.

As shown, the bridge desirably comprises a plurality of artificial teeth illustratively four in number designated 71, 72, 73 and 74. The teeth are desirably assembled in two sets, each having a pair of teeth 71, 72 and 73, 74 and a crown 75, 76 rigidly affixed respectively to the sides of teeth 71 and 74. As the formation of such teeth and crown and assembly thereof is well known to those skilled in the art, it will not be described. The tooth 72 has a pin 57' mounted therein in the manner previously described, so that it extends laterally outward from the side wall 77 of tooth 72 adjacent the biting surface 78 thereof and substantially parallel to the latter. The tooth 73 has a cup 59' mounted therein as by molding when the tooth is formed, with the mouth of the cup flush with the side wall 79 of said tooth 73 also adjacent the biting surface thereof.

In installing the bridge shown in Fig. 7, the end of the pin 57' extending from tooth 72 is inserted into cup 59' which is longitudinally aligned therewith and the bridge is positioned in the mouth of the patient so that the crowns 75, 76 may be pressed onto the previously prepared abutment teeth 81, 82 and retained thereon by suitable cement.

As the pairs of artificial teeth 71, 72 and 73, 74 are capable of relative longitudinal and rotary

75

movement, the crowns automatically adjust themselves as they are pressed into place so that they both will accurately fit on the previously prepared abutment teeth 81, 82 with no space between the gum line and the rim 83 of the mouth of the crown into which food may collect.

By reason of the positioning of the locking assembly adjacent the biting surface 78 of the artificial teeth 72, 73 there will be no relative pivotal movement between the sets of teeth 71, 72 and 73, 74 which might, if it occurred, exert leverage against the crowns to displace the associated abutment teeth with possible injury thereto.

It is to be noted that the abutment teeth 81 and 82 of the embodiment shown in Fig. 7 are substantially parallel and hence, the two sets of teeth 71, 72 and 73, 74 with their attached crowns may be assembled as above described and positioned in the mouth. Where, however, the abutment teeth are not parallel as shown in Fig. 2, both crowns could not be properly positioned on the abutment teeth simultaneously and the spring urged plunger assembly should be used in place of the fixed pin 57'. To install the bridge of Fig. 7 with a spring urged plunger when the abutment teeth 76, 81 are not parallel would merely require that first the set of teeth 73, 74 be affixed on abutment tooth 76 in conventional manner and then the set of teeth 71, 72, which would carry the plunger, be positioned on abutment tooth 81 so that the plunger would cam into the cup 59' in tooth 73 to lock the bridge in place.

As the outer end of the pin and plunger in all embodiments herein fits with close tolerance in the cup and also in the sleeve, there will be no relative lateral displacement between the abutment tooth 42 and artificial tooth 13 shown in Figs. 1 to 4; between abutment tooth 67 and artificial tooth 51 shown in Figs. 5 and 6, or between artificial teeth 72 and 73 shown in Fig. 7. Hence the bite of the user will be proper at all times.

It is of course to be understood that the crown and the inlay are interchangeable and either crowns or inlays or one of each could be used.

The constructions herein permit the slight longitudinal give afforded with natural teeth by reason of the relative longitudinal displacement afforded by the locking mechanism and hence there will be no uncomfortable rigidity present when the user bites into food.

As many changes could be made in the above construction and method, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A dental bridge comprising at least one artificial tooth, a sleeve extending laterally inward from one side of said tooth substantially parallel to the biting surface thereof and completely contained in said tooth, a locking member slidably mounted in said sleeve, resilient means in said sleeve normally urging said locking member out of said sleeve, means on said sleeve to limit the outward movement of said locking member, a cup to receive the outer end of said locking member and means rigidly mounting said cup.

2. A dental bridge comprising at least one artificial tooth, a sleeve extending laterally inward from one side of said tooth substantially parallel to the biting surfaces thereof and completely contained in said tooth, a plunger slidably mounted in said sleeve, said sleeve substantially preventing lateral displacement of the plunger therein, resilient means in said sleeve normally urging said plunger outwardly, means on said sleeve to limit the outward movement of said plunger, a cup to receive the outer end of said plunger, said cup preventing lateral displacement of the plunger therein and means rigidly mounting said cup.

3. The combination set forth in claim 2 in which the means to limit the outward movement of said plunger comprises a pin in said sleeve extending substantially radially inward and said plunger has an annular groove to receive the inner end of said pin.

4. A dental bridge to be mounted in a gap between a pair of abutment teeth, said bridge comprising at least one artificial tooth, anchoring means on one side of said tooth and rigid therewith, firmly to mount the latter to one of such abutment teeth, a sleeve extending laterally inward from the other side of said artificial tooth, substantially parallel to the biting surface thereof and completely contained in said tooth, a locking member slidably mounted in said sleeve, resilient means in said sleeve normally urging said locking member out of said sleeve, means on said sleeve to limit the outward movement of said locking member, a second anchoring means adapted to be rigidly affixed to the other abutment tooth and means rigidly mounted with respect to said second anchoring means to receive said locking member and to prevent lateral displacement of said artificial tooth with respect to such other abutment tooth.

5. A dental bridge to be mounted in a gap between a pair of abutment teeth, said bridge comprising at least one artificial tooth, anchoring means rigidly affixed to one side of said tooth firmly to mount the latter to one of such abutment teeth, a sleeve extending substantially laterally inward from the other side of said artificial tooth substantially parallel to the biting surface thereof and completely contained in said tooth, a plunger slidably mounted in said sleeve, said sleeve substantially preventing lateral displacement of the plunger therein, a coil spring in said sleeve normally urging said plunger outwardly therefrom, means on said sleeve to limit the outward movement of said plunger, a second anchoring means adapted to be affixed to the other abutment tooth and a cup rigidly affixed with respect to said second anchoring means to receive the plunger, said cup preventing lateral displacement of the plunger therein, thereby preventing lateral displacement of said artificial tooth with respect to such second abutment tooth.

6. A dental bridge to be mounted in a gap between a pair of abutment teeth, said bridge comprising at least one artificial tooth, anchoring means rigidly affixed to one side of said tooth firmly to mount the latter to one of such abutment teeth, a sleeve extending substantially laterally inward from the other side of said artificial tooth substantially parallel to the biting surface thereof and completely contained in said

tooth, a plunger, having an annular groove therein, slidably mounted in said sleeve, said sleeve substantially preventing lateral displacement of the plunger therein, a coil spring in said sleeve normally urging said plunger outwardly therefrom, a pin in said sleeve extending substantially radially inward into said annular groove to limit the outward movement of said plunger, a second anchoring means adapted to be affixed to the other abutment tooth and a cup rigidly affixed with respect to said second anchoring means to receive the plunger, said cup substantially preventing lateral displacement of the plunger therein thereby preventing lateral displacement of said artificial tooth with respect to such second abutment tooth.

7. The combination set forth in claim 6 in which the width of said annular groove in said plunger, the thickness of said pin and the location of the latter in the sleeve are so related that with the outer end of said plunger in its most advanced position said outer end is positioned in both the cup and the sleeve.

8. A dental bridge comprising at least one artificial tooth, anchoring means rigidly affixed to one side of said tooth, a sleeve extending substantially laterally inward from the other side of said artificial tooth, substantially parallel to the biting surface thereof and completely contained in said tooth, a plunger slidably mounted in said sleeve, resilient means in said sleeve normally urging said plunger outwardly therefrom, means on said sleeve to limit the outward movement of said plunger, a second anchoring means and means affixed in said second anchoring means to receive said locking member to prevent lateral displacement of said artificial tooth with respect to said second anchoring means.

9. A dental bridge to be mounted in a gap between a pair of abutment teeth, said bridge comprising at least one artificial tooth, a crown rigidly affixed to one side of said artificial tooth firmly to mount the latter to one of such abutment teeth, a sleeve extending substantially laterally inward from the other side of said artificial tooth, substantially parallel to the biting surface thereof and completely contained in said tooth, a plunger slidably mounted in said sleeve, resilient means in said sleeve normally urging the plunger outwardly therefrom, means on said sleeve to limit the outward movement of said plunger, a second crown adapted to be rigidly affixed to such other abutment tooth, and a cup affixed in said second crown adapted to receive the plunger to prevent lateral displacement of said artificial tooth with respect to such second abutment tooth.
